UNITED STATES PATENT OFFICE.

GORDON REES, OF EAST NEW ANNAN, NOVA SCOTIA, CANADA.

HANDLE FOR BLACKSMITHS' VISES.

1,422,478.

Specification of Letters Patent. Patented July 11, 1922.

Application filed June 11, 1921. Serial No. 476,815.

To all whom it may concern:

Be it known that I, GORDON REES, a citizen of the Dominion of Canada, residing at East New Annan, in the county of Colchester and Province of Nova Scotia, have invented certain new and useful Improvements 5 in Handles for Blacksmiths' Vises, of which the following is a specification.

The present invention relates to improvements 10 in blacksmiths' vises and the principal object is to provide a device of the character described in which the movable jaw element is automatically adjustable.

A further object is to provide a vise in 15 which the movable jaw element is capable of movement to or from the fixed jaw element by the adjustment of a lever in different directions.

With these and other objects in view, the 20 invention consists in the construction, combination and arrangement of parts as will be hereinafter fully described, illustrated in the accompanying drawings, and pointed out in the claims hereunto appended.

25 Figure 1 is a side elevational view of the improved vise.

Fig. 2 is a front end elevation of the same.

Fig. 3 is a vertical longitudinal section of the vise.

30 Fig. 4 is a fragmental elevation of the operating lever, illustrating the position of the pawl element with respect to the ratchet pinion, when the jaw is to be adjusted in one direction.

35 Fig. 5 is a similar view illustrating the relative position of the pawl and ratchet element when the jaw is to be adjusted in the opposite direction.

Fig. 6 is a vertical longitudinal section 40 of a bench vise embodying the invention, and

Fig. 7 is a front end of the same.

Referring to the drawings like numerals designate like parts in the various drawings.

The numeral 6 designates the fixed jaw of 45 the improved vise which in this instance is in the form of a blacksmith's anvil, which latter may be approximately secured by bolts to a work bench or supporting pedestal.

The stationary jaw 6 is formed with a 50 horizontal bore 7 extending approximately to the medial point, where it communicates with a counter-bore 8.

A movable jaw 9 is adapted for connection to the fixed jaw 6 and is formed with 55 a slide extension 10, which takes into the counter-bore 8, being provided at the oppo-

site side with key flanges 11 fitting into suitable channels in the said fixed jaw 6. The lower part of the movable jaw 9 and its extension 10, are formed with a bore 12 which latter registers with the bore 7 of the fixed jaw.

A shaft 13 extends through the bore 12 of the fixed jaw 6 and extension 10 and has its inner end formed with segmental teeth 14. 65 The walls of bore 7 are formed with segmental threads into which are received the segmental teeth 14 of the shaft 13. The outer end of shaft 13 extends outwardly of the movable jaw 9 and has keyed thereupon a 70 gear pinion 15. A lever 16 is loosely mounted on shaft 13 and is held against longitudinal movement by a nut 17 screwed upon the extreme end of the shaft. The lower end 18 of lever 16 is relatively thicker and wider 75 than the upper part and is apertured for the reception of a bolt 19, by means of which a pawl member 20 is pivotally mounted thereon. This pawl member 20 has its lower end formed with the oppositely disposed teeth 21 and 22, which when the lever 16 is actuated in either direction, engage the teeth of the gear pinion 15.

As the lever 16 is reciprocated the pawl member 20 is actuated to cause one of its 85 teeth to engage a tooth of the gear pinion 15. In this manner, the shaft 13 is revolved a portion of a revolution and consequently the segmental teeth 14 of the shaft 13 will engage the threads of bore 7. As the shaft 13 90 continues to be revolved, the extension 10 of the movable jaw 9 will be moved inwardly or outwardly depending upon the direction in which the lever 16 is reciprocated. To provide for the different adjustments of the movable jaw, with respect to the fixed jaw 6. The pawl member 20, may be swung around on its pivot 19 as indicated in Fig. 4, to position the same as indicated in Fig. 5. In the position indicated in Fig. 4 100 when the lever 6 is reciprocated to the left, the jaw 9 will be moved outwardly of the fixed jaw or anvil 6, and when the said lever is reciprocated to the right, the movable jaw 9 will be moved toward the fixed jaw 6 to 105 clamp the work therebetween.

The movable jaw 9 may be of any desired configuration depending upon the work to be held in the vise.

In the modified form illustrated in Fig. 6, 110 I provide what is commonly known in the art, as a bench vise, which comprises a stock

- or fixed jaw 23, the latter being adapted for connection to a work bench or support by bolts 24 which pass through openings 25 in the base of the stock. A movable jaw 26 is formed with an extension 27 of inverted U-shape in cross section, which latter extends through an inverted U-shaped slot in the stock. In consequence of this particular U-configuration a channel 28 is formed in the extension 27 which extends through the forward part of jaw 26 and terminates in the downwardly projecting wall portion 29. The stock 2 is likewise formed with a threaded opening which registers with a smooth bore 30 in the wall portion 29 of the movable jaw 26. A shaft 31 is formed with a toothed portion 32 which takes into the threaded opening of the stock 23 while its outer end extends through the bore 30 of the movable jaw 26. That part of the shaft 31 extending beyond the movable jaw 26, has keyed thereto a pinion 33 and loosely mounted thereon a lever 34. A collar 35 is secured by a screw 36 to the shaft 31 and engages the inner face of the wall extension 29 preventing the outward movement of shaft 31, while a nut 37 is secured by screw 38 to the outer end of shaft 31 to hold the lever 34 thereon and to prevent the longitudinal displacement of the shaft. A pawl member 39 has pin connection 40 with lever 34 and is adapted for engagement with the pinion 33 when the lever 34 is reciprocated in either direction to move the jaw 26 to or from the fixed stock jaw 23.
- In both the preferred and modified forms, when the lever is reciprocated the pawl member associated therewith, will engage the pinions and resultantly the toothed portion of the shaft will be given a partial revolution in the threaded bore of the fixed jaw, which advances or retracts the movable jaw, depending of course upon the direction in which the lever is moved, as the lever is loosely mounted on the shaft and the pinion fixedly secured thereto, when the limit of adjustment of the lever is reached, the pawl will grip the pinion and cause the same to be moved with the lever, and vice versa.
- It is obvious that I have provided a device, whereby quick adjustment of the movable element of the vise is attached.
- From the foregoing it is thought that the construction of my invention, will be clearly understood, and therefore, a more extended explanation has been omitted.
- Having thus described my invention what I claim as new is:—
1. A vise comprising a fixed jaw, a movable jaw connected to said fixed jaw, said fixed jaw formed with a bore and counter bore, an extension formed on said movable jaw and adapted for location within said counter bore, a shaft extending through said movable jaw and extension, said shaft having a toothed section extending through the said bore, a pinion fixedly secured to said shaft, an operating lever loosely mounted on said shaft, a pawl member pivotally connected to said lever and said pawl member adapted for engagement with said pinion when the said lever is reciprocated in either direction to advance or retract the said movable jaw with respect to said fixed jaw.
  2. The combination with an anvil, having a bore and counter bore, of a vise comprising a jaw element connected to said anvil, an extension formed on said jaw element and adapted for adjustment within the counter bore of said anvil, a shaft extending through said jaw and extension said shaft having formed with a toothed section, disposed within the anvil bore, a pinion fixedly mounted on said shaft, a lever loosely mounted on said shaft, a pawl member pivotally connected to lever, and said pawl adapted for engagement with said pinion to actuate said movable jaw to or from said anvil.
  3. A bench vise comprising a stock, a movable jaw adapted for association with said stock, said stock formed with a channel, an extension integral with the movable jaw, a shaft extending through said jaw and stock, a pinion fixedly mounted on said shaft, a lever loosely mounted on said shaft, a pawl member pivotally connected to said lever, said pawl member adapted for engagement with said pinion when said lever is reciprocated in either direction and said pawl member being adapted for adjustment to revise the operation of the said shaft.

In testimony whereof I affix my signature in the presence of two witnessess.

GORDON REES.
